(57) **CLAIM**

The ornamental design for a vacuum pump, as shown and described.

DESCRIPTION

FIG. 1 is a perspective view of a vacuum pump showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 in FIG. 6 with the internal parts omitted thereof.

The broken line portions of the vacuum pump in all views represent unclaimed portions of the claimed design and form no part thereof.
